UNITED STATES PATENT OFFICE.

PERCY L. BILLINGSLEY, OF ORLANDO, FLORIDA, ASSIGNOR TO ATLAS MANUFACTURING COMPANY OF ORLANDO, OF ORLANDO, FLORIDA.

LIFTING-JACK.

1,269,153.

Specification of Letters Patent. Patented June 11, 1918.

Application filed July 28, 1917. Serial No. 183,263.

To all whom it may concern:

Be it known that I, PERCY L. BILLINGSLEY, a citizen of the United States, residing at Orlando, in the county of Orange and State 5 of Florida, have invented certain new and useful Improvements in Lifting-Jacks; and I do hereby declare the following to be a full, clear, and exact description of the invention, such as will enable others skilled in 10 the art to which it appertains to make and use the same.

My invention relates to lifting jacks, and more particularly to a jack for jacking up the parts of an automobile or like vehicle 15 and which is capable of being readily collapsed into compact form wherein the jack may be conveniently carried in a tool box or kit of an automobile or like vehicle.

One of the objects of this invention is to 20 provide a jack of this character provided with novel means for preventing lateral movements of the parts of the jack with respect to its base, whereby to render stability to the jack and maintain its head in aligned 25 operative relation to the base of the jack.

Another object of this invention is to provide the jack with means to limit the inward movement of its collapsible members at their 30 central pivotal points so as to maintain the pivotal points of the collapsible members in alignment with each other when the jack is in set-up position so as to obviate the necessity for lifting the load upon the jack before the jack can be brought to collapsed position 35 and thereby eliminate undue wear and strain upon the parts of the jack which would be the inevitable results if there were not means provided to prevent such contingencies.

Another object of this invention is to produce a lifting jack of this character which is simple in construction, durable, efficient to accomplish the objects sought to be obtained, economical to manufacture, and constructed in a manner whereby the same may be readily and cheaply repaired.

These and other objects and advantages will more fully appear as the nature of the invention is more clearly understood from 50 the following description taken in connection with the accompanying drawings wherein there is disclosed one embodiment of the invention, but which is susceptible to numer-

ous variations and alterations in the form, construction, and arrangement of the parts 55 to meet the exigencies of the case without departing from the spirit of the invention or exceeding the scope of the claims.

Referring to the accompanying drawings: Figure 1 is a side elevation of the invention showing the same in set-up or extended 60 position, certain of the parts being broken away.

Fig. 2 is a vertical sectional view on line 2—2 of Fig. 1, showing further detail construction of the invention.

Fig. 3 is a vertical sectional view on line 3—3 of Fig. 2, showing still further detail construction of the invention.

Referring to the drawings, wherein similar reference characters denote corresponding parts throughout the several views, 1 denotes the base member, which may be formed of any suitable material but preferably metal, and suitably secured upon the 75 base member 1 as by the bolts 2 or other suitable securing means are the attaching flanges 3 of the spaced and oppositely disposed parallel side plates 4, provided adjacent, their upper edges with the pair of 80 spaced openings 5, the openings of one plate being in registration with the openings of the opposing plate.

Revolutely mounted in the registering openings 5 of the plates 4 are the trunnions 6 of the oppositely disposed blocks or substantial drums 7, provided upon their contiguous faces with the plurality of elongated transversely disposed ribs or teeth 8 which are maintained in constant mesh with each 90 other. The blocks or drums 7 are positioned between the side plates 4 and have formed thereon and between the adjacent ends of the blocks or drums 7 and the inner walls of the side plates 4 the non-circular shoulders 9.

Snugly embracing the shoulders 9 of the blocks 7 are the lower ends of the flanges 10 of the oppositely disposed lower collapsible channel bars 11, which lower ends are 100 formed with openings corresponding to the shape of the non-circular shoulders 9 of the blocks or drums 7. The upper ends of the flanges 10 of the lower channel bars 11 are provided with the apertured ears 12 in which 105 are revolutely mounted the trunnions 13 of

the blocks 14, one of the blocks 14, however, being provided with internal right hand screw threads 15 and the other of the blocks 14 being provided with the internal left hand screw threads 16.

Pivotedly mounted upon the trunnions 13 of the blocks 14 and between the apertured ears 12 of the bars 11 and the blocks 14 are the lower apertured ends 17 of the flanges 18 of the upper oppositely disposed collapsible channel bars 19, the channel bars 19 being formed of less width than the channel bars 11 so as to provide for the positioning of the lower apertured ends 17 of the bars 19 upon the trunnions 13 of the blocks 14 and between the apertured ears 12 of the channel bars 11. The upper ends 20 of the flanges 18 of the upper channel bars 19 are provided with non-circular openings for snugly embracing the non-circular shoulders 21 formed at the ends of the blocks or substantial drums 22 which are also provided with the trunnions 23 revolvably mounted in the spaced pairs of registering openings 24 formed in the oppositely disposed spaced parallel side plates 25 of the cap or head 26 of the jack. The contiguous faces of the oppositely disposed blocks or drums 22 are provided with the plurality of transversely disposed elongated teeth or ribs 27 which are maintained in constant mesh with each other. Upon the head 26 is suitably secured the plate 28 which not only reinforces the head 26 but provides an efficient support for the object to be raised. In order to reinforce the toggle bars of the jacks the bars 11 are provided with the reinforcing plates 29 which are secured to the backs of the bars through the medium of the rivets 30 or other suitable securing means, and to reinforce the bars 18 the same are provided upon their backs with the reinforcing plates 31 also secured to the bars 18 through the medium of the rivets 32 or other suitable securing means.

For operating the toggle bars 11 and 19 toward and away from each other at their central pivotal points there is threaded through the blocks 14 the threaded rod or bar 33 provided with the right hand threads 34 upon one end portion thereof and the left hand screw threads 35 upon the other end portion thereof, the right hand threads 34 engaging the internal threads 15 of one of the blocks 14 and the left hand threads 35 engaging the internal threads 16 of the other of the blocks 14 and for rotating the threaded rod or bar 33 with any suitable form of wrench or tool one end of the rod or bar 33 is provided with the non-circular head 36, and to prevent the central pivotal points of the toggle bars 11 and 19 from being moved inwardly toward each other and beyond alinement with their extreme pivotal points 65 a portion of the threaded rod or bar 33 be-

tween the adjacent ends of the threads 34 and 35 is left blank and may also be enlarged at this point so as to provide the annular rib, collar or shoulder 37 and against which the inner faces of the blocks 14 contact and thus provide a stop for preventing further inward movement of the central pivotal connections of the toggle bars toward each other.

The operation of the invention will be briefly described as follows:

Assuming the jack to be in collapsed position with its head substantially resting upon its base and the upper channel bars 19, seated within the lower channel bars 11 which position can be readily understood by the construction and manner of assembling the parts of the jack, and if it is desirable to raise an object, the jack is positioned with its head beneath the object to be raised and the screw threaded bar or rod 33 is revolved by any suitable wrench or tool in a manner for causing the right hand block 14 to move inwardly upon the threads 34 and the left hand block 14 to also move inwardly along the threads 35, whereby the object will begin to be raised and if necessary the rotating of the bar 33 may be continued until the inner faces of the blocks 14 contact with the shoulder, collar or annular rib 37 whereby the rotation of the threaded bar 33 and the inward travel of the blocks 14 thereon will be checked at the point when the central pivotal points of the toggle bars and their extreme pivotal points are in strict vertical alinement and the jack in its greatest extended position and at the same time the blocks being checked in their inward movement by the stop collar 37 the central pivotal points of the toggle bars will be prevented from passing inwardly beyond their vertical alinement with their extreme pivotal points and thereby lowering the head of the jack in such a manner as to require the raising or lifting of the load or weight or object before the toggle bars can be moved outwardly from each other at their central pivotal points by the reverse rotating of the threaded bar 33 and thus eliminate unnecessary strain upon the parts of the jack as well as wear and tear upon the threads of the blocks 14 and the threads of the bar 33, and in the operation of the device the lower end of the bars 11 and the upper ends of the bars 19 will swing in the plates 4 of the base and the plates 25 of the head by having their non-circular apertured ends snugly engaging the non-circular shoulders 9 and 21 of the blocks or drums 7 and 22 which have their trunnions 6 and 23 revolvably mounted in the openings 5 and 24 of the base and head respectively of the jack, and by the provision of the oppositely disposed blocks or drums 7 and 22 provided with the transversely disposed elongated teeth or ribs 8 and 27 re-

spectively and which are maintained in constant mesh with each other it is impossible for the head of the jack to become displaced from its operative relation with the base in 5 any lateral direction and by employing the channel bars 11 and 19 instead of flat links the stability of the jack is rendered more certain and efficient.

The respective parts of the jack may be 10 formed of any suitable material preferably metal, but I preferably form the bars 11 and 19 from plates of steel or iron by stamping the metal to the shape shown in the drawings, that is, channel shape or substantially 15 U-shape in cross section so as to provide these bars with sufficient rigidity for sustaining heavy weights and at the same time to be possessed of lightness of weight and being of angular formation and operating 20 in conjunction with the toothed or ribbed drums efficiently prevents swaging of the jack.

Having described my invention, what I claim as new and desire to secure by Letters Patent, is:—

1. A jack of the character specified, comprising a base, a head, connecting members between said base and said head, means for actuating said connecting members for moving said head to and from said base, and removable intercoacting means separate from but co-operating with said connecting members to maintain uniform movement of said connecting members.

35 2. In a jack embodying a supporting base, two pairs of members pivoted together to form a parallelogram, a head at the top connected to the upper pair of members, means for directly forcing said members to and 40 from each other to raise and lower said head, and removable gear members interposed between the pairs of members at the top and bottom to cause each pair of members to simultaneously partake of each 45 other's movement.

3. A device of the character specified, comprising a base provided with spaced flange members, a head provided with spaced flange members, upper and lower channel 50 bars connecting the flange members of said base and said head, means for pivotally connecting said channel bars together, means for drawing said channel bars toward and away from each other for moving said head toward and away from said base, removable gear, means rotatably mounted upon said base and upon said head and removably but nonrotatably connected with the upper and lower ends of said channel bars for preventing movement of said head out of operative vertical alignment with said base, and means for preventing the inward movement of said channel bars toward each other beyond a predetermined point.

65 4. A device of the character specified, com-

prising a base member, a head, a co-acting pair of drums revolvably mounted in said base, a co-acting pair of drums revolvably mounted in said head, a plurality of intermeshing teeth upon the contiguous faces of 70 each pair of drums, lower channel bars having their lower ends mounted upon the drums within said base member, upper channel bars having their upper ends mounted upon the drums within said head, means for 75 pivotally connecting the adjacent ends of said lower and said upper channel bars, means for drawing said channel bars toward and away from each other for moving said head toward and away from said base, and 80 means for preventing the inward movement of said channel bars toward each other beyond a predetermined point.

5. A device of the character specified, comprising a base member, a head, a co-acting pair of drums revolvably mounted in said base, a co-acting pair of drums revolvably mounted in said head, a plurality of intermeshing teeth upon the contiguous faces of each pair of drums, lower channel bars having their 90 lower ends mounted upon the drums within said base member, upper channel bars having their upper ends mounted upon the drums within said head, internally screw threaded blocks having trunnions for pivotally connecting together the adjacent ends of said channel bars, a threaded rod engaging the internal threads of said blocks for drawing said blocks and said channel bars toward and away from each other for operatively moving said head relative to said base, and a collar upon said screw threaded rod for limiting the inward movements of said blocks toward each other for preventing the movement of said channel bars inwardly 105 beyond a predetermined point.

6. A device of the character specified, comprising a base member, a head, a co-acting pair of drums revolvably mounted in said base, a co-acting pair of drums revolvably mounted in said head, a plurality of intermeshing teeth upon the contiguous faces of each pair of drums, non-circular shoulders upon each of said drums, lower channel bars having their lower ends mounted upon said non-circular shoulders of said lower drums, upper channel bars having their upper ends mounted upon the non-circular shoulders of said upper drums, means for pivotally connecting the adjacent ends of said lower 110 and said upper channel bars, means for drawing said channel bars toward and away from each other for moving said head toward and away from said base, and means for preventing the inward movement of said channel bars toward each other beyond a 115 predetermined point.

7. In a device of the character specified, the combination of a base member, a head, connecting members for said base member 120

and said head, and means for operating the meeting ends of said connecting members for moving said head relative to said base member; with coöperating drums revolubly mounted in said base member and said head and having non-circular interfitting connections with said connecting members for pivotally mounting said connecting members upon said base member and said head and

for causing simultaneous movement between 10 said connecting members and said drums.

In testimony whereof I have signed my name to this specification in the presence of two subscribing witnesses.

PERCY L. BILLINGSLEY.
